WEARING APPAREL CONVEYER

Ben Handler, North Bergen, N. J., assignor, by
mesne assignments, to Arthur Imerman Under-
garment Co., Inc., a corporation of New Jersey

Application January 2, 1947, Serial No. 719,792

7 Claims. (Cl. 198—131)

1

This invention relates to apparatus for use in examining various articles of wearing apparel for defects or poor workmanship or for use in removing or trimming from the articles loose ends of threads, bindings, etc., in the operations of inspecting and finishing the articles.

The primary object of the invention is the provision of apparatus which is well adapted to facilitate the inspecting and trimming operations and to reduce the time and labor required for those purposes.

Another object is the provision of means for holding or supporting the articles in positions in which the articles can be quickly and easily inspected and trimmed, thus relieving the operators from the burden of holding and handling the articles in order to perform these operations.

A further object is to provide for convenient adjustment of the article-supporting means for articles of different sizes so that the same apparatus may be used for articles of various sizes.

A yet further object of the invention is to provide apparatus of the character designated above with means automatically operable to deliver the inspected and trimmed articles in such positions in which they may be easily folded in the operation of removing them from their supports or holders.

The above and objects, features and advantages of the invention will be fully understood from the following description, reference being had to the accompanying drawings which are to be considered as illustrative of the invention but not in limitation thereof.

In the drawings:

Fig. 1 is a top plan view of apparatus embodying the present invention;

Fig. 2 is a sectional view on the line 2—2 of Fig. 1, and the base of one of the garment supports being shown in section;

Fig. 3 is a longitudinal sectional view of the apparatus on the line 3—3 of Fig. 1;

Figs. 4 and 5 are detail sectional views on the lines 4—4 and 5—5, respectively, of Fig. 1;

Fig. 6 is a sectional view of a garment support on the line 6—6 of Fig. 2.

Referring now to the drawings in detail, the apparatus comprises a work bench 10 at which several operators may be positioned side by side for performing the examining and/or trimming operations. Said bench also provides a supporting frame for an endless conveyor 12 which, as here shown is preferably of the horizontal endless-belt type. A plurality of article-supporting means 14, which are of the construction subse-

2

quently described herein, are carried by the conveyor and are movable thereby longitudinally of the bench 10 from one end thereof, at which garments are placed on said supporting means in succession, to the opposite or delivery end from which the garments are removed. In the course of travel of said article-supporting means from one end of the bench to the other, the articles are examined and are trimmed to remove loose thread ends, tape ends, etc., a motor-operated cutter held in the operator's hand being preferably used for this purpose.

The conveyor comprises a flat endless belt 16 engaging the driving pulley 18 and the pulley 20 which is at the delivery end of the conveyor. The belt-driving pulley 18 is fixed to a rotary shaft 21 which is power actuated. Said shaft is journaled for rotation in bearings 22 which are preferably adjustably movable longitudinally of the belt in brackets 24 for adjusting the longitudinal tension or tautness of the belt, the bearing adjusting screw members being indicated at 26. Pulley 20 is fixed to a rotary shaft 28 which is journaled for rotation in bearings provided in brackets or shaft supports 30.

The top of the bench 10 has a longitudinally extending opening 32 which is defined by the laterally spaced longitudinal channel rails 34, the upper surfaces of which are preferably flush with the top of the bench. Similar channel rails 36 are mounted in the bench frame below the top thereof. Rails 34 and 36 are supported in vertically spaced relation, at longitudinally spaced points by cross frame members 38 and 40. Companion cross bars 42 and 44 are secured by bolts 46 or in any other suitable way to belt 16 in sets spaced longitudinally of the belt, there being a set of such bars for each article-support or holder 14. Bars 42 and 44 are disposed transversely of the belt and project laterally therefrom at both of the side edges of the belt. The projecting portions of said bars are slidable in the channels of rails 34 and 36 for guiding the belt in its movement and for supporting the belt and the load carried thereby. The rails 34 and 36 are provided with curved members 48 and 50, respectively, for guiding the companion bars 42, 44 into said rails, respectively, during the belt movement from left to right viewing Fig. 1. As will presently appear bars 42 provide means for securing the article-supporting means or holders 14 to belt 16.

The article holders 14 comprise open frames on which the garments, indicated in dotted lines at 56 G in Fig. 3, are placed for inspection and for sup-

porting the garment for the trimming operation. As here shown, each holder comprises a base which includes a flat bar or rod 52 provided with longitudinal slots 54. For a purpose which will hereinafter clearly appear, the frame is mounted for turning movement about a vertical axis. Said mounting comprises a pivot pin 56 which is secured to a companion bar 42 and passes through a circular bearing opening 58 in a bearing block 60 which is fixed to the frame base-bar 52. Said pivot pin projects through an opening 62 in bar 52 and is provided at its outer end with a head here shown as a washer 64 held by a cotter pin 66. A spring 68 surrounds pin 56 and bears against said head thereof and against base-bar 52, thus holding the frame resiliently in position on bar 42 for pivotal movement about the axis of said pin. A washer 71 is disposed between bar 42 and block 60. Springs 68 prevent loose turning movement of the frames and hold them releasably in the positions in which they are turned.

The open frames of the article-holders 14 are adjustable so that garments of different sizes may be mounted thereon in optimum or spread condition for inspection and for the trimming operation. Each open frame comprises the laterally spaced vertical members 70 and 72 having their lower ends adjustably secured in a companion slot 54 of base-bar 52 by the nuts 74 and 76, the latter being preferably a wing nut and washers 78 are provided as shown. The frame members 70 and 72 have companion members 80 and 82 associated therewith, the latter being threaded into bar 52 and block 60 as clearly shown in Fig. 2. Lock nuts 84 are provided as indicated. Members 80 and 82 are provided at their upper ends with lateral tubular parts 86 in which the lateral parts 88 at the upper ends of the frame members 70 and 72, are respectively received in adjustable sliding relation therein. It will be noted that parts 86 form the top of the frame and that members 70 and 72 form the sides of the frame, and it will be understood that when a garment is placed on the frame, members 70 and 72 having been adjusted laterally of each other in respect to the space therebetween, for the particular size of the garment, hold the latter in laterally distended condition. Further, it will be understood that when the garment is thus held on the frame, light may pass therethrough so that it may be thoroughly examined for defects or poor workmanship, and at the same time loose ends of threads or of binding tapes, etc., may be readily located so that they may be cut off. In Fig. 3, the garment G is indicated as a bifurcated undergarment, for example a panty-garment, but it will be understood that other garments may be placed on the frame for inspection and trimming. Also, it will be noted that when the frames with the garments arrive in succession at the delivery end of the conveyor, they may be readily removed from their respective frames by slipping them off said frames.

The removal of the garments from the frames, at the delivery end of the conveyor, is facilitated by the pivotal mounting of the frames and by means provided in the apparatus, in accordance with the preferred embodiment of the invention as illustrated, for automatically turning each frame from a position in which the frame is disposed in a vertical plane extending in the direction of belt movement, i. e., longitudinally of the belt, to a position in which the frame is disposed in a plane extending transversely of the belt and in a horizontal plane as indicated at B in Fig. 3,

and for thus turning said frames, the apparatus is provided with suitable means which as here shown comprises a frame-turning member 90 which is fastened at one end thereof to the top of the bench 10 as indicated at 92 and which has a part 94 extending transversely of the path of travel of the frames for engagement by the bent rods 96 which are fixed to and project from the blocks 60 of the companion frame bases respectively. The part 94 is inclined in the direction of travel of the frames and is cleared by pin 96 at the end of a frame-turning movement of about 90°. Following the turning of the frame to its position transversely of the belt, the continued travel of the belt carries the turned frame over pulley 20 to the horizontal frame-position, indicated at B, at the delivery end of the apparatus.

The frames thus turned in succession continue to travel while the garments are removed therefrom at the delivery end and thereafter travel with the lower run of the belt in the reverse direction, i. e., toward the opposite end of the conveyor, and during such reverse travel said frames remain in their positions transversely of the belt. However, when the frames reach the upper run position of the belt they are turned to restore them to their positions in planes disposed longitudinally of the belt. For this purpose frame-turning means is provided on the top of bench 10. Said frame-turning means is secured at one end thereof to the top of the bench, as indicated at 99 and has a curved bar 100 which extends across the travel of the frames on the upper run of the belt in position, as at the start of the upper run which is at the left of said upper run, viewing Fig. 1, to engage the base-frames 52 for turning the frames in succession from their transverse positions to their longitudinal positions.

In the event that the frames are displaced somewhat from their longitudinal positions, during their travel on the upper run of the belt, said frames are accurately positioned longitudinally of the belt before said frames reach the frame-turning member 90. For this purpose, the correcting means 102 is provided in position to engage the base-frames 52 in succession to position the frames in correct relation to member 90 whereby the end of rod 96 is disposed in correct position in relation to part 94 of member 90. Positioning means 102 comprises a bar secured to the top of the bench 10 as indicated at 104 and has a part 106 which engages the edges of the frame-bases 52 in succession just before the frames travel to the point of bench 10 at which they are turned to their transverse positions.

While I have shown and described the preferred embodiment of my invention, it will be understood that the latter may be embodied in various other ways and without necessarily including all of the features of the invention, and that various changes in the details of construction and in the arrangement of parts may be made without departing from the underlying idea or principles of the invention within the scope of the appended claims.

Having thus described my invention, what I claim and desire to secure by Letters Patent is:

1. In apparatus of the designated character having an endless conveyor having upper and lower runs, a plurality of open frames carried by said conveyor in spaced relation thereon, each of said frames comprising laterally spaced vertical members having an open space therebetween and positioned to engage a garment placed on the frame and to hold the garment in spread condi-

tion across said open space, said frames being mounted on said conveyor for turning about the vertical axis of said frames, respectively, means disposed at the upper run of said conveyor near the receiving end thereof and engageable with said frames for turning them about said axes, respectively, thereof from positions in which said frames are disposed transversely of said run to positions in which said frames are disposed longitudinally of said run, and means engageable intermittently by said frames in timed relation to the movement of said conveyor for turning said frames about their respective axes from said last mentioned positions thereof to said first mentioned position thereof in which each frame is disposed before reaching the lower run of said conveyor, said conveyor being an endless belt and each of said frames being pivotally mounted on said belt and extending outwardly therefrom.

2. In apparatus of the designated character having an endless conveyor having upper and lower runs, a plurality of open frames carried by said conveyor in spaced relation thereon, each of said frames comprising laterally spaced vertical members having an open space therebetween and positioned to engage a garment placed on the frame and to hold the garment in spread condition across said open space, said frames being mounted on said conveyor for turning about the vertical axis of said frames, respectively, means disposed at the upper run of said conveyor near the receiving end thereof and engageable with said frames for turning them about said axes, respectively, thereof from positions in which said frames are disposed transversely of said run to positions in which said frames are disposed longitudinally of said run, and means engageable intermittently by said frames in timed relation to the movement of said conveyor for turning said frames about their respective axis from said last mentioned positions thereof to said first mentioned positions thereof in which each frame is disposed before reaching said delivery point of the conveyor, the two frame-turning means being disposed at opposite sides of the vertical axis of said frames, said conveyor being an endless belt and each of said frames being pivotally mounted on said belt and extending outwardly therefrom.

3. In apparatus of the designated character having an endless belt conveyor, a plurality of laterally adjustable open frames carried by said conveyor in spaced relation thereon, each of said frames comprising laterally spaced vertical members having an open space therebetween and positioned to engage a garment placed on the frame and to hold the garment in laterally distended condition across said open space, each of said frames having a base which is secured to and overlies said belt, and means for securing said vertical frame members to said base for relative adjusting movement of said frame members toward and away from each other on said base, said base having a pivotal movement in relation to said belt about a vertical axis whereby to provide for the turning of the companion frame.

4. In apparatus of the designated character having an endless conveyor, a plurality of laterally adjustable open frames carried by said conveyor in spaced relation thereon, each of said frames comprising laterally spaced vertical members having an open space therebetween and positioned to engage a garment placed on the frame and to hold the garment in laterally distended condition across said open space, vertical members disposed between said first-mentioned vertical members

spaced relation thereto, adjustable cross members extending between said first-mentioned vertical members and adjacent one of said other vertical members, respectively, at the upper ends thereof and forming the top of the frame, and means for adjustably securing the lower ends of said first-mentioned vertical members for adjusting the space therebetween, said last mentioned means comprising a lower cross member having slots in which said lower ends of said first mentioned members are positioned and fastening means releasably engageable with said lower ends and said lower cross members, and means including pivot pins connecting said lower cross members, respectively, to said conveyor, said frames turnable about said pivot pins respectively.

5. In apparatus of the designated character having an endless conveyor, a plurality of open frames carried by said conveyor in spaced relation thereon, each of said frames comprising laterally spaced vertical members having an open space therebetween and positioned to engage a garment placed on the frame and to hold the garment in laterally distended condition across

20 said open space, vertical members disposed between said first-mentioned vertical members in spaced relation thereto, adjustable cross members extending between said first-mentioned vertical members and adjacent ones of said other vertical members, respectively, at the upper ends thereof and forming the top of the frame, and means for adjustably securing the lower ends of said first-mentioned vertical members for adjusting the space therebetween, each of said cross members

25 comprising a tubular part extending laterally from one of said other vertical members toward an adjacent one of said first-mentioned vertical members and the latter having a laterally extending part which is slidably engaged in said tubular part.

30 6. In apparatus of the designated character having an endless conveyor, a plurality of open frames carried by said conveyor in spaced relation thereon, each of said frames comprising laterally spaced vertical members having an open space therebetween and positioned to engage a garment placed on the frame and to hold the garment in laterally distended condition across said open space, vertical members disposed between said first-mentioned vertical members in spaced relation thereto, adjustable cross members extending between said first-mentioned vertical members and adjacent ones of said other vertical members, respectively, at the upper ends thereof and forming the top of the frame, and means for adjustably securing the lower ends of said first-mentioned vertical members for adjusting the space therebetween, each of said cross members

35 comprising a tubular part extending laterally from one of said other vertical members toward an adjacent one of said first-mentioned vertical members and the latter having a laterally extending part which is slidably engaged in said tubular part.

40 7. In apparatus of the designated character having an endless conveyor, a plurality of open frames carried by said conveyor in spaced relation thereon, each of said frames comprising laterally spaced vertical members having an open space therebetween and positioned to engage a garment placed on the frame and to hold the garment in laterally distended condition across said open space, vertical members disposed between said first-mentioned vertical members in spaced relation thereto, adjustable cross members extending between said first-mentioned vertical members and adjacent ones of said other vertical members, respectively, at the upper ends thereof and forming the top of the frame, and means for adjustably securing the lower ends of said first-mentioned vertical members for adjusting the space therebetween, each of said cross members

45 comprising a tubular part extending laterally from one of said other vertical members toward an adjacent one of said first-mentioned vertical members and the latter having a laterally extending part which is slidably engaged in said tubular part.

50 8. In apparatus of the designated character having an endless conveyor, a plurality of open frames carried by said conveyor in spaced relation thereon, each of said frames comprising laterally spaced vertical members having an open space therebetween and positioned to engage a garment placed on the frame and to hold the garment in laterally distended condition across said open space, vertical members disposed between said first-mentioned vertical members in spaced relation thereto, adjustable cross members extending between said first-mentioned vertical members and adjacent ones of said other vertical members, respectively, at the upper ends thereof and forming the top of the frame, and means for adjustably securing the lower ends of said first-mentioned vertical members for adjusting the space therebetween, each of said cross members

55 comprising a tubular part extending laterally from one of said other vertical members toward an adjacent one of said first-mentioned vertical members and the latter having a laterally extending part which is slidably engaged in said tubular part.

60 9. In apparatus of the designated character having an endless conveyor, a plurality of open frames carried by said conveyor in spaced relation thereon, each of said frames comprising laterally spaced vertical members having an open space therebetween and positioned to engage a garment placed on the frame and to hold the garment in laterally distended condition across said open space, vertical members disposed between said first-mentioned vertical members in spaced relation thereto, adjustable cross members extending between said first-mentioned vertical members and adjacent ones of said other vertical members, respectively, at the upper ends thereof and forming the top of the frame, and means for adjustably securing the lower ends of said first-mentioned vertical members for adjusting the space therebetween, each of said cross members

65 comprising a tubular part extending laterally from one of said other vertical members toward an adjacent one of said first-mentioned vertical members and the latter having a laterally extending part which is slidably engaged in said tubular part.

10 10. In apparatus of the designated character having an endless conveyor having upper and lower runs, a plurality of open frames carried by said conveyor in spaced relation thereon, each of said frames comprising laterally spaced vertical members having an open space therebetween and

75 11. In apparatus of the designated character having an endless conveyor having upper and lower runs, a plurality of open frames carried by said conveyor in spaced relation thereon, each of said frames comprising laterally spaced vertical members having an open space therebetween and

positioned to engage a garment placed on the frame and to hold the garment in spread condition across said open space, said frames being mounted on said conveyor for turning about the vertical axis of said frames, respectively, means disposed at the upper run of said conveyor near the receiving end thereof and engageable with said frames for turning them about said axes, respectively, thereof from positions in which said frames are disposed transversely of said run to positions in which said frames are disposed longitudinally of said run, and means engageable intermittently by said frames in timed relation to the movement of said conveyor for turning said frames about their respective axis from said last mentioned positions thereof to said first mentioned positions thereof in which each frame is disposed before reaching the delivery point of the conveyor, said two frame-turning means being

5 disposed at opposite sides of the vertical axes of said frames, and means disposed between said two frame turning means for accurately positioning said frames before reaching the second of said frame turning means.

BEN HANDLER.
